UNITED STATES PATENT OFFICE.

WILLIAM WENDERHOLD AND CHARLES UEBELMESSER, OF NEW YORK, N. Y.,
ASSIGNORS TO CRU PATENTS CORPORATION, A CORPORATION OF NEW
YORK.

BELT CONNECTION.

1,397,750.

Specification of Letters Patent. Patented Nov. 22, 1921.

Application filed December 13, 1917. Serial No. 206,882.

To all whom it may concern:

Be it known that we, WILLIAM WENDERHOLD and CHARLES UEBELMESSER, a citizen of the United States, and a citizen of the 5 German Empire, respectively, residing at New York city, in the county and State of New York, have invented certain new and useful Improvements in Belt Connections, of which the following is a clear, full, and 10 exact description.

Our invention relates to couplings and connections, more particularly for use with steel bands.

The object of the invention is to provide 15 couplings that are simple, easily made and also adaptable to the smallest diameter pulleys.

It is a well known fact that steel bands are better conveyers of power than leather 20 and are also more efficient, more durable and much cheaper to manufacture.

The difficulty heretofore experienced was that there was no simple, reasonably cheap 25 coupling available, and after long and many experiments we have perfected a number of simple couplings for use on steel belts.

As shown in our drawings, our couplings can all be mounted easily, and the peculiar 30 construction thereof guard against breaking at the joints of the belt.

Referring to the drawings,

Figure 1 is a cross-section through one type of coupling.

Fig. 2 is a top view of Fig. 1.

Fig. 3 is a cross-section through slightly modified construction embodying our invention.

Fig. 4 is a top view of Fig. 3.

As shown in Fig. 1 the steel band 1 is 40 broken off and only two ends are shown. C and D are the ends which are laid around the guard blocks 8 and 9. Between 8 and 9 are two concave blocks 10 and 11. The entire is held together by screws 12. This 45 type of connection makes a very substantial coupling.

As shown in Fig. 3, this type is substantially the same as that shown in Fig. 1,

with the exception of the center block 13 being one piece instead of two pieces as 10 50 and 11.

Many other modifications have been made and tested by us, and the most practical have been set forth in this application, as giving the greatest durability against break- 55 age of the belts and insuring a most satisfactory and safe gripping surface with the pulley with which the coupling and belt co-operate.

While we have shown and described specific structures embodying the principles of our invention, we wish it to be understood that our invention is to be limited or restricted only in accordance with the scope of the attached claims and various changes 60 65 in details of construction will readily appear to those skilled in the art coming within the spirit and scope of our invention.

What we claim as our invention is:

1. A belt coupling comprising a pair of 70 convex members, a central block member having a concave face to correspond to and to coöperate with the convexity of the pulley, said block member also having concave contour surfaces to form a snug fit 75 with said convex members and adapted to receive the belt ends between the same and said convex members, and means for clamping 80 said members and said belt ends together.

2. A belt coupling comprising a pair of convex members, a central block member of concave contour to form a snug fit with said convex members and adapted to receive the belt ends between the same and said convex 85 members, said central block member having a concave face corresponding to the convexity of a pulley with which said block member coöperates, and a screw passing through said members and said belt ends to 90 clamp the same together.

Signed at the city, county and State of New York, this 8th day of December, one thousand nine hundred and seventeen.

WILLIAM WENDERHOLD.
CHARLES UEBELMESSER.
